E. W. ALDRIDGE

MATTRESS

Filed Nov. 20, 1922

FIG. 1.

FIG. 2.

FIG. 3.

E. W. Aldridge
INVENTOR

G. H. Baker

BY Victor J. Evans

ATTORNEY

WITNESS:

UNITED STATES PATENT OFFICE.

ERNEST W. ALDRIDGE, OF VINSON, OKLAHOMA.

MATTRESS.

Application filed November 20, 1922. Serial No. 602,200.

To all whom it may concern:

Be it known that I, ERNEST W. ALDRIDGE, a citizen of the United States, residing at Vinson, in the county of Harmon and State 5 of Oklahoma, have invented new and useful Improvements in Mattresses, of which the following is a specification.

The object of this invention is to provide an air mattress comprising two independent 10 longitudinal sections, each having an air inlet controlled by the valve, so that one or both sections may be inflated, according to the need of the user.

A further object is to provide a mattress 15 comprising two longitudinal sections of sheet rubber, covered with cloth, with transverse strips and fastening devices for connecting the sections in such manner that both will lie in the same parallel plane when 20 inflated, the strips or straps being disconnected when one section only is used, in order that the one used portion may be folded over the other, and allowed to remain idle.

25 With the foregoing and other objects in view, the invention consists in the novel construction and arrangement of elements described, illustrated and claimed, it being understood that modifications may be made 30 within the scope of the claims without departing from the spirit of the invention.

In the accompanying drawings, Figure 1 is a top plan view of the mattress; Figure 2 is a side or edge elevation, and Figure 3 is 35 a vertical transverse section, broken away.

The two longitudinal sections of the mattress are designated 10 and 12, and each comprises four sides and two end walls. One side, which will be termed the bottom, extends 40 the full width of the mattress, and in fact, a single width of sheet rubber may include also the edge portions 12', the tops 13 and 14 for the two sections, and the inner edge portion 15. The edges of the sheet of rubber as distinguished from the edges of the mattress sections, are secured under a central longitudinal strip 16, just above the bottom thickness.

Middle reinforcing strips are designated 45 16' and extend entirely around each mattress

section and binding strips 18 reinforce all of the corners. The opposite end walls of the sections are shown at 19 and 20. The mattress so formed of sheet rubber is covered by a thickness of fabric 22, and short straps 23 are secured by fastening devices 24, so that 55 the two sections may be directly connected when both are to be used. If only one section is required, the straps are released and the idle section is folded over the other. 60

Air inlet connections are shown at 25 and 26, in the end portions of the respective sections, and valves 27 close the connection. When deflated the mattress may be folded 65 into very small compass, and is specially adapted for the use of campers, being readily inflated by any air pump, such as a tire pump, and not being affected by moisture. The mattress will be maintained in a sanitary condition; and is also adapted for 70 use in hotels and in sleeping cars.

What I claim is:—

1. A mattress comprising two longitudinal sections, hingedly connected, valved air inlet connections for the respective sections, 75 and means for connecting the sections adjacent to one surface of the mattress, said sections being otherwise independent permitting the sections to be folded over one another when inflated and when deflated. 80

2. A mattress comprising two longitudinal sections, hingedly connected, valved air inlet connections, for the respective sections, means connecting the sections along a central longitudinal line adjacent to one surface of the mattress, and detachable devices 85 for connecting said sections near the opposite surface of said mattress.

3. A mattress formed of two longitudinal sections including a single width of material extending across the bottom of the two sections, thence along the outer edge portions and across the top of said sections, inwardly to the center, and thence along the inner edges of the separate sections, downwardly to the bottom thereof, and detachable 90 means for connecting adjacent portions of said sections. 95

In testimony whereof I affix my signature.
ERNEST W. ALDRIDGE.
